UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

DESIGN FOR A COUCH-HAMMOCK.

No. 40,132.

Specification for Design.

Patented July 6, 1909.

Application filed March 16, 1909. Serial No. 483,861. Term of patent 14 years.

To all whom it may concern:

Be it known that I, ISAAC E. PALMER, a citizen of the United States, residing at Middletown, in the county of Middlesex and State of Connecticut, have invented a new, original, and ornamental Design for Couch-Hammocks, of which the following is a specification, reference being had to the accompanying drawing, forming part thereof.

The figure is a perspective view of a couch hammock showing my new ornamental design.

I claim:

The ornamental design for a couch hammock, as shown.

ISAAC E. PALMER.
